UNITED STATES PATENT OFFICE.

HORACE E. GILL, OF YONKERS, NEW YORK, ASSIGNOR TO FAN FLAME SPARK PLUG CO., OF YONKERS, NEW YORK, A CORPORATION OF NEW YORK.

SPARK-PLUG.

1,392,933.

Specification of Letters Patent. Patented Oct. 11, 1921.

Application filed October 9, 1918. Serial No. 257,502.

To all whom it may concern:

Be it known that I, HORACE E. GILL, a citizen of the United States, residing at Yonkers, in the county of Westchester and

5 State of New York, and having a post-office address at #217 McLean Ave., Yonkers, New York, have invented certain new and useful Improvements in Spark-Plugs, of which the following is a full, clear, and

10 exact specification.

My invention relates to improvements in spark plugs, and particularly to the use in connection therewith of a new form of gas tight gasket by which the likelihood of 15 breakage of the porcelain insulator is very largely reduced. In the construction of standard spark plugs, a porcelain insulator is used of a generally cylindrical form and provided about midway of its length with

20 an annular enlargement, the insulator being clamped between the two parts of a metal shell and two gaskets being employed for preventing the leakage of gas between the shell and said insulator. These gaskets are

25 located above and below the annular enlargement of the insulator and have heretofore been made of thin copper or other sheet metal with a suitable filling of asbestos. In cross section such gaskets as here-

30 tofore made are shaped like a trough with the asbestos filling inserted therein and facing outwardly. In other words, such gaskets have been in the form of small annular troughs with asbestos or other resilient circumferences. In clamping the parts of

35 such a spark plug together, as heretofore constructed, the metal sections of the shell have compressed the metal of the gaskets into tight engagement with the insulator at the point or angle where the said enlarged portion meets the cylindrical

40 body of the insulator. By reason of this tight engagement made necessary to secure a gas tight joint, and also by reason of changes in temperature in use there is danger of the insulator becoming cracked

45 particularly in line with the upper gasket, and of course when such a crack or break occurs the spark plug has to be discarded. In an examination of many hundreds of

50 cracked porcelains I have observed that a very large part of them cracked and broke in line

with the upper gasket. In order to overcome this difficulty, I make use of a gasket above the enlargement of the porcelain and preferably below the same also, in which the asbestos or other elastic filling is reversely 60 arranged; or in other words, in which the asbestos faces inwardly instead of outwardly. In this way when the gasket is applied in position and pressure imposed thereon so as to deform the same, the asbestos packing will be squeezed out and an elastic material will be brought into contact with the porcelain instead of a hard, practically non-elastic metal as with present practice. In this way I secure even a bet- 65 ter joint than is now possible so far as its gas tight character is concerned, and at the same time I very materially reduce the danger of breakage and cracking of the 70 insulator owing to the elastic nature of the 75 pressure imposed upon it. In fact the improvement is so marked as practically to reduce entirely the danger of cracking the insulator which has heretofore been a potent 80 source of annoyance and expense in connection with spark plug manufacture.

In order that my invention may be better understood, attention is directed to the accompanying drawing forming part of this specification and in which Figure 1 is a 85 cross sectional view of a portion of a standard spark plug on an enlarged scale showing the present manner of arranging the gaskets therein; and Fig. 2, a similar view illustrating my improvements. 90

Referring first to Fig. 1, the insulator 1 is made of porcelain in the usual way and contains the usual central electrode 2. The insulator 1 is formed with the enlargement 3 as heretofore and is contained within a 95 shell composed of a lower part 4 and an upper part 5 screwed therein. Gaskets 6 and 7 have been arranged as shown between the parts of the shell 4-5 and the enlargement 3. Under present practice these gas- 100 gaskets are arranged as illustrated being formed of a thin sheet of copper with a filling 8 of asbestos or similar elastic material. As now made the gaskets are now arranged as shown in Fig. 1 with the asbestos facing outwardly 105 so that the metal part of each gasket when the sections 4 and 5 are screwed together is forced tightly against the porcelain and breaks or cracks are likely to form therein, substantially as indicated by the dotted lines 110

9 and 10. Ordinarily breakages at the line 9 coincident with the upper gasket are far more numerous than those at the line 10 corresponding to the lower gasket.

- 5 Referring to the Fig. 2, I assemble all parts together in the same way as in Fig. 1, except that the upper gasket 7 is reversed as is preferably also the case with the lower gasket 6. With this construction the as-
10 bestos 8 faces inwardly instead of outwardly so that when pressure is applied, squeezing the sections 4 and 5 together, an elastic material presses against the porcelain instead of a hard, unyielding material as in Fig. 1.
15 In this way I practically do away entirely with breaks and cracks in the porcelain and at the same time it becomes possible to screw the sections 4 and 5 more tightly together than at present so as to insure a tighter joint
20 between the shell and porcelain.

Having now described my invention, what I claim as new therein and desire to secure by means of Letters Patent is as follows:

1. In a spark plug, the combination with
25 a vitreous insulator provided with an integral annular enlargement and a two-part shell surrounding the same, of a single gasket interposed between said shell and insulator and comprising an annular metal
30 trough with an elastic packing therein, the

exposed face of said packing facing inwardly and being forced into tight and intimate contact with the vitreous insulator adjacent to the shoulder formed by said enlargement and thus constituting the packed joint be-
35 tween the insulator and shell, substantially as set forth.

2. In a spark plug, the combination with a vitreous insulator provided with an integral annular enlargement, and a two-part 40 shell surrounding the same, of a single gasket interposed between said shell and insulator above the enlargement and a single gasket interposed between said shell and insulator below the enlargement, each of said gaskets 45 comprising an annular metal trough with an elastic packing therein, the exposed faces of said packings facing inwardly and being forced into tight and intimate contact with the vitreous insulator adjacent to the shoul-
50 der formed by said enlargement and thus constituting the packed joints between the insulator and shell, substantially as set forth.

This specification signed and witnessed 55 this seventh day of October, 1918.

HORACE E. GILL
